UNITED STATES PATENT OFFICE.

CORNELIUS B. CORCORAN, OF NEW YORK, N. Y., ASSIGNEE TO UNDERWOOD TYPE-WRITER COMPANY, OF NEW YORK, N. Y., A CORPORATION OF DELAWARE.

TYPEWRITING MACHINE.

Application filed December 11, 1919. Serial No. 344,083.

To all whom it may concern:

Be it known that I, CORNELIUS B. CORCORAN, a citizen of the United States, residing in borough of the Bronx, in the county of the Bronx, city and State of New York, have invented certain new and useful Improvements in Typewriting Machines, of which the following is a specification.

This invention relates to signals for typewriters, such as are used to warn the operative of the approach to the end of a line of writing; and an object of the invention is the improvement generally of the operating means for such signals, and also the provision of a signal that will adequately warn that the end of the line of writing is near.

In the Underwood typewriter, to which my improvements are applied, it is customary to lock the type-keys at the end of the line of writing, and also to sound the bell a few letter-spaces prior to that space at which the key-lock becomes effective, such signal-bell acting as a warning to the operative that the end of the line is about to be reached. It may sometimes happen that the operative may forget that the signal has been sounded, as it is customary to sound it but once, and may attempt to write a word of more letters than there are letter-spaces between that letter-space at which the signal sounds and the letter-space at which the keys become locked.

A feature of the present invention, therefore, relates to the provision of means for giving a signal, such as the sounding of a bell, at each of a succession of letter-space positions of the carriage next preceding that letter-space at which the key-locking means becomes operative. In order that the power to operate the signal-bell may be efficiently employed, said power is preferably taken directly from the spring which impels the carriage in its letter-spacing movements. Preferably, too, the bell-sounding means is normally disconnected from the power means that actuates it, and connections are provided whereby the typewriter-carriage renders the bell-sounding means effective on reaching a predetermined, but variably adjustable, letter-space position, the carriage holding the bell-sounding means effective for a sufficient time, to permit the bell to be sounded a succession of times as the carriage continues to space. The signal-actuating

means may preferably take the form of a disk, driven from the carriage-spring-drum, said disk having pins projecting from its face, to engage and operate tappets, connected to bell-hammers.

Other features and advantages will hereinafter appear.

In the accompanying drawings,

Figure 1 is a side elevation of an Underwood typewriting machine, embodying my improvements.

Figure 2 is a front elevation of the left-hand portion of the typewriter-frame and carriage.

Figure 3 is a detail, showing a bell-hammer in raised position, under the action of a pin on the pin-disk; and

Figure 4 is a perspective view, showing the signal-actuating mechanism in normal position.

Referring to the drawings, and particularly to Figure 1, type-keys 1, pivoted at 2, are connected through intermediate levers 3 to type-bars 4, each of which, on depression of a key-lever, is adapted to be driven upwardly and rearwardly against the front face of a platen 5, supported in a carriage 6. The carriage is supported in the rear on a bar 7, on which it slides, and it is supported at its forward portion on a rod 8, by anti-friction roller 9 connected to the typewriter-carriage and engaging the rod 8. The usual spring-drum 10 is provided, in which is a coiled spring connected to the carriage at 11, for impelling the same forwardly. Connected to the carriage is a toothed bar 12, engaging a pinion 13, to which is connected an escapement-wheel 14, with which engage escapement-dogs 15 and 16, which are moved into and out of engagement with the escapement-wheel, under control of the keys, by means of a universal escapement-frame 17, as is customary in the Underwood machine.

The type-keys 1 have formed thereon projections 18, which are adapted to be engaged by a locking bar 19, forming part of a cradle, said cradle including end levers 20, of which the right-hand one is shown in Figure 1, and a supporting-rod 21, on which the cradle is mounted for pivotal movement. The locking bar may be operated to lock the keys, by means, usually provided in these machines, said means including a cam 22, carried by the typewriter-carriage; said cam being adapted

to engage and depress a member 23, which, when depressed, acts to rock a shaft 24, mounted for pivotal movement. The shaft 24 has a depending arm 25, carrying at its 5 end a pin 26, adapted to engage an arm 27, rigid with the rod 21, to rock the cradle and move the bar 19 underneath the projections 18, to thereby lock the keys against depression. As shown in Figure 2, the member 23 10 has a cam-surface 28, which is first engaged by the cam 22. As the carriage continues its step-by-step movement, the cam 22 depresses the member 23, said member being provided with a flat portion 29, and, when 15 the cam 22 is in engagement with this portion 29, the member 23 is held in its depressed position. During this time, the shaft 24 has been rocked, but not sufficiently for the pin 26 to engage the arm 27. Therefore, 20 the keys are not locked at this time. As the carriage continues its step-by-step movement, the cam 22 engages a projection 30 on the member 23, and further depresses the same, resulting in a further rocking of 25 the shaft 24, and, during this further rocking, the pin 26 engages and moves the arm 27, to render the key-lock effective. It will thus be seen that the member 23 and also the shaft have each an initial and a final movement, and it is this initial movement that is 30 availed of to control means to give adequate warning to the operative that the end of a line of writing is about to be reached, and that the keys are about to be locked.

35 In the present embodiment of the invention, this warning means preferably consists of a bell 31, and means for operating the bell at several successive letter-space positions of the carriage just prior to the operation of 40 the key-lock. Preferably, I provide a frame, consisting of a pair of levers 32 and 33, connected at their lower ends by a shaft 34, pivotally mounted between the levers. The levers at their upper ends are pivoted in a 45 bracket 35, connected to a portion 36 of the typewriter-frame. Pivotaly mounted on the shaft 34 are tappets 37 and 38, and connected to each tappet is a bell-hammer 39. Springs 40, one connected to each tappet below the shaft 34, normally urge the hammers towards the bell, but they are held from 50 actual contact therewith by lugs 41, one lug projecting from each of the levers 32 and 33, these lugs engaging the tappets under 55 action of the springs 40. It will, of course, be understood that the hammer-arms are sufficiently resilient, to enable the hammers to strike the bell when the tappets are tripped. Power for tripping the tappets, to 60 thereby operate the line-signal-bell, is taken directly from the carriage-spring, and, for this purpose, a disk 42 is connected to the carriage-drum by means of studs 43. The disk 42 is provided with pins 44, projecting 65 from each face thereof, the pins on one face

being alternately arranged with respect to the pins on the opposite face. As the carriage-drum rotates, the pin-disk 42 rotates with it, and the distance between the center of a pin on one face of the disk and the center of a pin on the opposite face thereof is equal to the distance the disk rotates during one step of movement of the carriage. The pin-disk and connections to the carriage-spring thus constitute actuating means for 75 the hammers.

Normally, the frame, carrying the tappets, is in the position shown in Figure 4, with the tappets out of range of movement of the pins on the disk, so that, during the major 80 portion of the line of writing, no signal is sounded. However, when the carriage approaches the end of the line of writing and the cam 22 depresses the member 23, means are provided for rendering the pins effective 85 to actuate the tappets, to operate the signal. This means preferably consists of a slide 45, having a pin-and-slot connection at 46 with the depending arm 25. Said slide 45 is guided by pins 47 engaging slots in the slide, 90 one of which is shown at 48, Figure 4, and said slide at its end remote from the depending arm is provided with a cam 49, which engages an arm 50, connected to, or forming part of, the lever 33, said lever 33 otherwise 95 being identical with the lever 32. Movement of the slide acts to move the lever-frame, and thereby the tappets into the path of movement of the pins 44, the tappet 37 engaging the pins on the right-hand side of 100 the disk, as viewed in Figure 4, and the tappet 38 engaging the pins on the left side thereof. Therefore, as the disk 42 moves step by step, concomitantly with the step-by-step movement of the typewriter-carriage, the bell-hammers will be alternately tripped, and the bell will be sounded at each letter-space during the time the tappets are in operative position with respect to the actuating pins 44; and it will be seen that this 105 engagement will be maintained while the cam 22 is passing over the surface 29 of the member 23. As the carriage moves on, the cam 22 engages the projection 30, moving the depending arm into its final position to 110 lock the keys.

Variations may be resorted to within the scope of the invention, and portions of the improvements may be used without others.

Having thus described my invention, I 120 claim:

1. In a typewriting machine, the combination with type-keys, of a letter-spacing carriage movable step by step under control of said keys, a lock for said keys, means for operating said lock at any of a plurality of letter-space positions of said carriage, means rendered effective by said operating means for giving a signal at each of a succession of letter-space positions of said carriage, 130

and means for subsequently rendering said lock effective.

2. In a typewriting machine, the combination with a traveling carriage, of type-keys controlling said carriage, a line-lock for operating said keys, a bell, a cam on said carriage, for rendering said line-lock effective, and means brought into action by said carriage-cam, for causing said bell to sound 10 a plurality of times during movement of said carriage just prior to the rendering effective of said line-lock.

3. In a typewriting machine, the combination with a carriage movable step-by-step, of type-keys controlling said carriage, a line-signal, comprising a bell and a rotatable disk movable step by step with said carriage, means carried by said disk, adapted to ring said bell at each step of the disk, and means 20 controlled by the carriage, for determining which steps of said disk shall be effective in ringing said bell.

4. In a typewriting machine, the combination with a carriage movable step by step, of type-keys controlling said carriage, a line-signal, comprising a bell and a rotatable disk movable step by step with said carriage, pins projecting on either side of said disk, near the periphery thereof, two hammers for said bell, pivoted adjacent said disk, tappets carried by said hammers, projecting towards said pins, but normally not in position to contact therewith, and means for moving said tappets into the path of said pins, to be engaged thereby as said disk rotates to thereby ring said bell.

5. In a typewriting machine, the combination with a carriage movable step by step, of type-keys controlling said carriage, a line-signal, comprising a bell and a rotatable disk movable step by step with said carriage, pins projecting on either side of said disk, near the periphery thereof, the pins on one side of said disk being alternately arranged with respect to the pins on the other side, two hammers for said bell, pivoted adjacent said disk, tappets carried by said hammers, projecting towards said pins, but normally not in position to contact therewith, and means for moving said tappets into the path of said pins, to be engaged thereby as said disk rotates to thereby ring said bell.

6. In a typewriting machine, the combination with a carriage movable step by step, of type-keys controlling said carriage, a line-signal, comprising a bell and a rotatable disk movable step by step with said carriage, pins projecting on either side of said disk, near the periphery thereof, two hammers for said bell, pivoted adjacent said disk, tappets carried by said hammers, projecting towards said pins, but normally not in position to contact therewith, and means controlled by the carriage on reaching a prede-

termined position, for moving said tappets into the path of said pins, to be engaged thereby as the disk rotates to thereby ring the bell.

7. In a typewriting machine, the combination with a traveling carriage, of type-keys controlling the same, a line-lock for said keys, a trip-lever having an initial movement and a final movement, and acting on its final movement to render said lock effective, 70 a line-signal, comprising a rotatable disk, pins projecting on either side of said disk, near the periphery thereof, a bell, two hammers therefor, pivoted adjacent said disk, and tappets carried by said hammers, projecting towards said pins, but normally out of position to contact therewith, and means controlled by said trip-lever, during its initial movement for moving said tappets into the path of said pins, to be engaged 75 thereby as said disk rotates to thereby ring the bell.

8. In a typewriting machine, the combination with a letter-spacing carriage, of type-keys controlling the same, a line-signal-bell, 90 a hammer therefor, a tappet connected to said hammer, means moving step by step with said carriage, for engaging and operating said tappet, a pivoted frame carrying said tappet, and normally occupying a position 95 with said tappet out of range of said step-by-step moving means, a cam for engaging said frame, for moving said tappet into range of said step-by-step moving means, and means controlled by said carriage for 100 operating said cam.

9. In a typewriting machine, the combination with a letter-spacing carriage, of type-keys controlling the same, a line-signal-bell, a hammer therefor, a tappet connected 105 to said hammer, means moving step by step with said carriage, for engaging and operating said tappet successively, a pivoted frame carrying said tappet, and normally occupying a position with said tappet out of range 110 of said step-by-step moving means, a cam for engaging said frame, for moving said tappet into range of said step-by-step moving means, and means controlled by said carriage, for operating said cam.

10. In a typewriting machine, the combination with a letter-spacing carriage, of type-keys controlling the same, a line-signal-bell, a plurality of hammers therefor, a tappet connected to each hammer, a disk 120 movable step by step with said carriage, said disk having pins alternately arranged on either side thereof, for engaging and operating said tappets, a pivoted frame carrying said tappets, a cam for engaging said frame, 125 for moving said tappets into range of said disk, and means controlled by said carriage, for operating said cam.

11. In a typewriting machine, the combination with a letter-spacing carriage, of type-

keys controlling the same, a line-signal-bell, a hammer therefor, a tappet connected to said hammer, means moving step by step with said carriage, for engaging and operating said tappet successively, a pivoted frame carrying said tappet, and normally occupying a position with said tappet out of range of said step-by-step moving means, a cam for engaging said frame, for moving said 10 tappet into range of said step-by-step moving means, and means controlled by said carriage, for operating said cam when the carriage reaches a predetermined position, and holding said cam in moved position during 15 several letter-space movements of the carriage, whereby said tappet is operated successively, to give a plurality of signals.

12. In a typewriting machine, the combination with a step-by-step letter spacing carriage, of type-keys controlling the same, a line-lock for said keys, a line-signal-bell, a hammer therefor, a tappet for actuating said hammer, means moving step by step with said carriage, for engaging and operating said tappet successively, a pivoted frame carrying said tappet, a cam for engaging said frame, for moving said tappet into range of said step-by-step moving means, and means controlled by the carriage, for operating said cam when said carriage reaches a predetermined position, and holding said cam in moved position dur-

ing several letter-space movements of said carriage, whereby said tappet is operated successively, to give a plurality of signals, 35 said carriage on further movement acting to render said line-lock effective on said type-keys.

13. In a typewriting machine, the combination with a frame part and a carriage part 40 movable step by step on the frame part, and type-keys controlling said movement of the carriage, of a line-signal bell and a hammer therefor and a tappet member connected to the hammer, and all mounted upon one of 45 said parts, an operating member for the tappet mounted upon the other said part and having a series of projections engageable with the tappet member for repeatedly ringing the bell, the member mounted on the 50 frame being normally out of the path of travel of the member mounted on the carriage, and means operated by the carriage on reaching a predetermined position for moving one of said members, so that said 55 member on the frame will be in the path of travel of said member on the carriage to be engaged thereby during further travel of the carriage for repeatedly ringing the bell.
